UNITED STATES PATENT OFFICE.

ORA WOOD WILLIAMS, OF MINNEAPOLIS, MINNESOTA.

GRAIN SEPARATOR.

Application filed December 8, 1921. Serial No. 521,002.

To all whom it may concern:

Be it known that I, ORA WOOD WILLIAMS, a citizen of the United States, residing at Minneapolis, in the county of Hennepin 5 and State of Minnesota, have invented certain new and useful Improvements in Grain Separators; and I do hereby declare the following to be a full, clear, and exact description of the invention, such as will enable 10 others skilled in the art to which it appertains to make and use the same.

My present invention is especially intended as an improvement on the type of grain separator disclosed and claimed in my 15 pending application Serial Number 511,727, filed October 31, 1921, but involves certain features that are capable of general application to separators of the type wherein the separation is made by drums, cylinders or the 20 like equipped with pockets. The chief novelty of the present invention is directed to an improved form of pocket for more effectually accomplishing the separation of materials of different size and shape, such as 25 the separation from wheat of oats, cockle, wild peas and various small seeds.

In the accompanying drawings, which illustrate the invention, like characters indicate like parts throughout the several views.

Referring to the drawings:

Fig. 1 is a view partly in end elevation and partly in transverse vertical section illustrating the several features of my invention as incorporated in a separator of the 35 general type disclosed in my said prior application;

Fig. 2 is a fragmentary transverse section showing a portion of the separating drum, a portion of the hopper which is located there- 40 in and a blast-producing device that is located outside of the drum;

Fig. 3 is a face view or elevation looking at the inner pocketed surface of the drum and showing but a fragment thereof;

Fig. 4 is a section on the line 4—4 of Fig. 3;

Fig. 5 is a fragmentary view corresponding to Fig. 3 but showing the pockets on a larger scale; and

Fig. 6 is a section on the line 6—6 of Fig. 5.

The numeral 7 indicates the separating drum or cylinder, the same, as shown, having exterior flanges 8 that run in curved 55 supporting rollers 9. Within the drum is a collecting hopper 10 formed at the axis of

the drum with a semi-cylindrical depression in which, as shown, is a spiral conveyor 11. The drum may be rotated by any suitable means.

The inner surface of this drum or cylinder is provided with pockets of very peculiar and novel form, best illustrated in Figs. 3 to 6, inclusive. These pockets are formed by deep concave depressions 12 that are elongated transversely of the line of movement of the pockets and at their central portions have depending or downwardly extended discharge throats 13 that decrease in depth and preferably also in width, in a downward direction. By reference particularly to Figs. 4 and 6, it will be noted that the pockets 12 have much greater depth and that their bottoms are rounded in all directions. The discharge throats 13 are preferably approximately V-shaped in cross section and, at places where they join the pockets, have slightly greater depth than the pockets themselves. Moreover, the lower sides of the pockets are inclined or rounded so that there will be a tendency of small seeds to roll, under the action of gravity, from the extremities of the pockets to the bottoms of the discharge throats and from thence downward to the diminished ends of the throats.

For the separation of oats and other foreign materials from wheat, the pockets 12 are made of such size that they will receive freely the largest kernels of wheat but are 90 not long enough to receive oats. They will, of course, receive all of the smaller seeds, such as cockle, wild peas, wild mustard and other small seeds. On the rising side of the drum, the pockets will carry all of these 95 seeds or materials upward, but all of the round small seeds will quickly run into the discharge throats and out of the pockets. As the oats cannot get completely into the pockets, they will also quickly fall into the 100 discharge throats and slip from the pockets. The wheat, however, can fall deep into the pockets and, hence, will be carried to a much higher point than any of the other seeds or materials. In fact, the oats and other foreign seeds will run from the pockets before they have been carried upward as high as the edge of the hopper 10, but the wheat will be carried above the hopper and, when finally discharged, will drop into the hopper. 110

For some classes of work, the efficiency of the machine may be increased by using

a blast device for hastening the downward movement of the oats, small seeds and the like, from the pockets. Such a device is illustrated in Fig. 1 and comprises an air delivery tube 14 that extends through the drum below the hopper and is provided with upwardly extended discharge nozzles 15 that have depending deflecting flanges 16 that direct the blast directly downward over the upwardly moving pocketed surface of the drum. The wheat being deeply seated in the pockets, will not be disturbed by this downward blast, but the other materials, as they run toward or into the discharge throats 13, will be caught by the downward blast and their downward movement will be greatly hastened thereby. The wheat, when seated in the pockets, will be supported by engagement of its ends with the end portions 20 of the pockets and with its central portion free from the lower deepest portion of the discharge throat.

The numeral 17 indicates spiral conveyors such as illustrated in my prior application, 25 which work over the lower surface of the drum for ejecting therefrom the oats and other rejected foreign materials. The numeral 18 indicates a deflecting plate shown as supported from the air pipe 14 and overlying the upper spiral conveyor 17 to prevent the downward air blast from acting directly thereon.

For insuring the discharge of all of the wheat from the pockets after it has been carried above the hopper, I may employ an air blast device comprising an air tube 19, provided adjacent to the outer surface of the drum with discharge perforations 20 and air-confining flanges 21. To render this device effective, the pockets 12 are provided with small air passages 22 that lead from the bottoms thereof outward through the drum, (see particularly Fig. 2).

What I claim is:

- 45 1. A separating surface formed with pockets having centrally depending discharge throats that downwardly decrease in depth.
2. A separating surface formed with pockets that are elongated transversely of the di-

rection of movement thereof and are formed 50 with centrally depending discharge throats.

3. A separating surface formed with pockets that are elongated transversely of the direction of movement thereof and are formed 55 with centrally depending discharge throats that decrease both in depth and width in a downward direction.

4. A separating drum provided on its inner surface with pockets that are elongated transversely of the direction of movement of 60 said pockets, said pockets having centrally depending discharge throats.

5. A separating drum provided on its inner surface with pockets that are elongated transversely of the direction of movement of 65 said pockets, said pockets having centrally depending discharge throats that decrease in depth in a downward direction.

6. A separating surface formed with pockets having centrally depending discharge 70 throats, means for moving said pocketed separating surface upwardly, said pockets having perforated bottoms, and means for blowing a blast of air through the perforations of said pockets after they have reached 75 a predetermined altitude.

7. A separating drum provided on its inner surface with pockets that are elongated transversely of the direction of movement of 80 said pockets, said pockets having centrally depending discharge throats, means for rotating said drum, and means for blowing a blast of air downward over the upwardly moving pocketed surface of said drum.

8. A separating drum provided on its inner surface with pockets that are elongated transversely of the direction of movement of 85 said pockets, said pockets having centrally depending discharge throats, a hopper within said drum, means for rotating said drum, 90 the pockets of said drum having perforated bottoms, and means for blowing a blast of air through the perforated bottoms of said pockets after they have been moved to a position above said hopper.

In testimony whereof I affix my signature.

ORA WOOD WILLIAMS.
